WEIGHT INDICATOR FOR DEEP WELL DRILLING RIGS

Frank S. Bunker, Los Angeles, Calif., assignor, by
mesne assignments, to Laurence H. Heacock,
Compton, Calif.

Refiled for abandoned application Serial No.
408,819, November 21, 1929. This application
July 27, 1938, Serial No. 221,589

3 Claims. (Cl. 265—47)

This application is a substitute for abandoned application No. 408,819 filed November 21, 1929.

My invention relates to a weight indicator that is especially designed for use in connection with deep well drilling rigs, and the principal objects of my invention are, to provide a relatively simple apparatus that will give an accurate, direct reading or indication in tons, of the exact weight of the parts of the well drilling apparatus that are suspended from the travelling hook in the well derrick, at the same time compensating for the weight of the lines, travelling block and hook, friction of the lines over the sheaves and for the floatation or buoyancy of the mud or fluid in the well hole, further, to provide a weight indicator that will give a correct direct reading of the weight of tools and parts suspended from the travelling hook regardless of the number of supporting lines on the travelling block and further, to provide an indicator of the character referred to that will give a correct reading of that portion of the weight of the tools that bears on the bottom of the well hole, regardless of the number of supporting lines.

Further objects of my invention are, to generally improve upon and simplify the construction of the existing forms of drilling rig weight indicators, further, to provide an indicator that is capable of being readily combined with the standard forms of rotary well drilling rigs and further, to provide an indicator of the character referred to that is accurate in its indications to the variable weights of the parts of the drilling apparatus that are in the well hole and a portion of which indicator is capable of being easily and quickly adjusted so as to compensate for the number of "lines up" or the lines of cable between the travelling block and the sheaves of the crown block.

With the foregoing and other objects in view, my invention consists in certain novel features of construction and arrangement of parts that will hereinafter be more fully described and claimed and illustrated in the accompanying drawings, in which:

Fig. 1 is a diagrammatic elevational view of parts of a deep well drilling rig and showing my improved weight indicator associated therewith.

Fig. 2 is a vertical section taken approximately through the center of that portion of the indicator that includes the fluid container, the diaphragm associated with said container and the levers that are connected to the drill line and which actuate said diaphragm.

Fig. 3 is an elevational view of the parts illustrated in Fig. 2.

Fig. 4 is a face view of the gauge that forms a part of my improved indicator.

Fig. 5 is a vertical section taken on the line 5—5 of Fig. 4.

Referring by numerals to the accompanying drawings which illustrate a practical embodiment of my invention, 10 designates the derrick floor, 11 the calf wheel, 12 the draw works, 13 the drill line or cable, one end of which is connected to the draw works and the other end to the calf wheel and the intermediate portion of which cable has loops or portions 14 that pass over sheaves in the crown block and beneath sheaves 15 in the travelling block 15. This travelling block supports in the usual manner the swivelled hook 16, the latter carrying the usual swivelled elevator 17 and suspended from the latter is the upper member or kelly of the drill string and its tools.

All of the parts just described are well known in the art and form no part of my invention, except in combination the elements and mechanism that constitute my invention.

Suitably anchored on the derrick floor 10 or other suitable support, is a horizontally disposed block or plate 18 and projecting upwardly from the ends thereof are integral brackets 19 and 20. Bracket 19 is slightly higher than bracket 20 and the upper portions of both brackets are bifurcated for the reception of levers.

Passing through the bifurcated upper portion of bracket 19 is a horizontally disposed pin 21, upon which is fulcrumed one end of a horizontally disposed lever 22, which latter projects a short distance beyond the upper end of bracket 20 and this end of said lever is connected by a link or links 23 to the corresponding end of a lever 24 that is positioned directly beneath lever 22 and which is fulcrumed on a pin 25 that passes through the bifurcated upper end of bracket 20.

Arranged in an opening in base plate 18 between the brackets 19 and 20 is a metal bowl 26 on top of which is secured an elastic or flexible diaphragm 27, preferably of rubber. Arranged above this diaphragm is a cap 28, the edges of which are secured to base plate 18 by bolts or screws and formed in the center of this cap is a vertically disposed bearing 29.

Arranged for sliding movement through bearing 29 is a short vertically disposed rod 30 and carried by the lower end thereof is a disc 31 that bears on top of diaphragm 27.

The inner end of lever 24 bears on top of rod 30.

Formed through the intermediate portion of lever 22 is a series of connected apertures 32 and on the face of the lever directly below these apertures are the numbers "4", "6", "8" and "10" 5 and which numbers read from right to left. These numbers are intended to designate the number of "lines up" or the supporting lines that are disposed between the crown block and the traveling block.

10 Formed through the intermediate portion of lever 22 a short distance below and to the left of the aperture 32 that is numbered "10" is an aperture 33 that is utilized as a point of connection for the drill line or cable while a fishing 15 job is under way.

The lower ends of a pair of links or bars 34 are arranged on the sides of lever 22 and passing through the lower ends of said links and through any one of the apertures 32 is a pin 20 or bolt 35 having portions on opposite sides cut away in order that said bolt when turned into a horizontal position will pass between the narrow neck portions that connect the apertures 32. As 25 a result of this construction the pin or bolt 35 may be readily moved from one aperture 32 to another without entirely disengaging said pin or bolt from the lever and the lower ends of links 34. Bars 34 which are formed of metal provide a rigid connection between the cable 13 and the 30 lever 22, thus insuring positive transmission of all strains from the "lines up" to lever 22 and, such arrangement provides for increased accuracy of the indicated weights.

The upper ends of the links or bars 34 are 35 pivotally connected to a clamp comprising a tapered socket 36 that receives wedge-shaped slips 37 and which latter engage the drill line or cable 13 a short distance above the point where the same passes onto the calf wheel.

40 Under ordinary conditions that portion of the drill line or cable between the clamp comprising the socket 36 and slips 37 and calf wheel is slack, as illustrated in Fig. 1.

Located at a suitable point above the derrick 45 floor is a gauge that includes a housing 38 and located therein is a Bourdon tube 39 and connected to the lower end of the latter is a relatively small tube 40 that leads from the bottom of bowl 26.

50 Secured to the rear side of a drum 41 is an outwardly projecting internally threaded ring or collar 42 that is screw-seated on the externally threaded front portion of housing 38 and arranged within the drum against the rear face 55 thereof is a disc 43 bearing on its face two graduated scales. The graduated marks of one of these scales extend through the arc of approximately 315° or 320° and the marks of this scale are numbered from zero to 100 or more and reading clockwise. This scale and the pointer operating in connection therewith are designed to indicate the tons of weight that are suspended from hook 16 and adjacent to the center of this graduated scale appears the words "Tons on hook."

50 The relatively narrow space between the ends of the scale just described is provided with a graduated scale that is preferably printed in red and certain of the marks of this scale bear 70 the numbers "10," "20," "30," reading anticlockwise or from left to right. This last mentioned scale and the pointer that cooperates therewith are designed for indicating that portion of the weight of the drill string, tools, etc. that bears 75 on the bottom of the well hole and immediately

above this scale on the face of disc 43 appears the words "Tons on bottom."

Inasmuch as the structure just described includes two sets of graduated scales and two pointers cooperating therewith and such scales and pointers perform two functions, namely, to indicate the weight on the hook and the weight on the bottom of the hole, said structure may be properly termed a duplex pressure gauge.

Secured in the front portion of the drum 41 10 is a disc 44 of glass. Journalized in suitable bearings in the center of housing 18 is a shaft 45, the forward portion of which projects through an opening in the center of the disc 43 and secured on the forward end of this shaft is a double 15 ended pointer 46, one end of which is colored red, as designated by 47—a and this end of the pointer is adapted to cooperate with the red scale that indicates "Tons on bottom." The opposite end portion 47 of this pointer is preferably painted 20 black and it cooperates with the "Tons on hook" graduated scale.

Mounted on shaft 45 within housing 38 is a pinion 48 and meshing therewith is a toothed rack 49 that is connected by a link 50 with the 25 end of the Bourdon tube opposite to the end to which tube 40 is connected.

Secured to the periphery of drum 41 is a small cable 51 that passes several times around the drum and the ends of said cable depend from opposite sides of the drum.

Leading from tube 40 to a suitably located housing 52 is a small tube 53 and located within said housing is a recording gauge with clock, chart and pen.

Connected to tube 53 is a small manually operable pump 53—a by means of which liquid may be pumped into the tubes 53 and 40 to replenish liquid that may escape therefrom.

The arrangement of the levers 22 and 24 and 40 the adjustability of the bolt 35 in the connected apertures 32 is such that the point of application of force or pull of the drill line or lever 22 is such as that the over all ratios are 25 to 1, 16½ to 1, 12½ to 1 and 10 to 1.

45 Thus the pull of the weight on the dead line through the compound levers is impressed on plunger 30 and disc 31 which latter bears on the flexible or elastic diaphragm 27 and forces liquid from the bowl 26 through tube 40 to the Bourdon 50 tube 49 and the movement of the latter is transmitted to shaft 45 that carries the double ended pointer 46.

The constant direct ton reading is obtained by 55 having the proper ratio for the number of supporting lines, for instance:

25 to 1 for 4 lines equals 4 times 25 which equals 100;
16½ to 1 for 6 lines equals 6 times 16½ which 60 equals 100;
12½ to 1 for 8 lines equals 8 times 12½ which equals 100;
10 to 1 for 10 lines equals 10 times 10 which equals 100.

65 The proper ratio for the number of "lines up" is a constant and the effective hydraulic area of the fluid container is a constant. The pressure per square inch in the fluid container as a given weight on the hook is therefore a constant 70 times a constant and is therefore always the same (a constant).

For practical purposes the bowl or fluid container 26 has an effective (arbitrary) area of 40 square inches. For a gauge pressure of 32 75

pounds produced by the upward pull of the dead line with any assumed number of "line up" is as follows: pressure per square inch multiplied by 40 multiplied by the number of "lines up" multiplied by ratio. Number of "lines up" multiplied by ratio multiplied by 40 equals constant 4000.

$$\begin{array}{r} 4000 \\ \hline 2000 \end{array}$$

10

equals two tons weight per pounds gauge pressure and therefore 32 pounds gauge pressure equals 64 tons.

In operation the tubes 53, 40 and bowl 26 are filled with liquid and the bolt 35 is inserted through the aperture 32 that corresponds with the number of supporting lines or "lines up" between the crown block and travelling block. The weight impressed on lever 22 will act through lever 24, rod 30, disc 31, fluid within bowl 26 and tube 40 and through Bourdon tube 39 to actuate the pointer 46 so that the black end 47 thereon will indicate on the "Tons on hook" scale, the weight of the travelling block, hook and elevator.

By pulling on one end of cable 51 the drum 40 is rotated until the zero of the "Tons on hook" scale is brought to a point directly opposite the end of the black pointer 47 and thus compensation has been effected for the weight of the travelling block, its hook and friction of the "lines up" over their sheaves. As sections of drill pipe are now added to the drill string the weight of the added sections will in succession be indicated by the movement of the black pointer 47 over the "Tons on hook" scale.

When the lower end of the drill string reaches the bottom of the well hole the string is drawn upwardly approximately two or three feet and the total weight on the hook will now be indicated by the black pointer 47 on its graduated scale.

By pulling on the cable 51 the drum 40 is now rotated until the graduated mark zero is directly opposite the red end 47-a of the pointer after which the drill string is lowered onto the bottom of the well hole and the red end 47-a of the pointer will now register on the "Tons on bottom" graduated scale, the exact portion of the weight of the drill string resting upon the bottom.

Simultaneous with the registration of the weights as just described upon the graduated scales of the gauge, a permanent record of the weights will be made by the action of the liquid that passes through tube 53 and actuates the recording gauge within the housing 52.

In the event that fishing operations for a broken tool or broken drill string are necessary, the lower ends of the bars 34 are connected to lever 22 by bolt 35 which passes through aperture 33. Inasmuch as this aperture is located a greater distance from the fulcrum of lever 22 than the connected apertures 32, the sensitivity of the recording apparatus is materially increased and as a result the operators are able to readily determine whether or not the fishing tool has engaged the broken drill string or tool.

Thus it will be seen that I have provided a weight indicator for deep well drilling rigs that is relatively simple in construction, capable of being readily combined with the standard forms of rotary drilling rigs and which indicator is very effective in performing the functions for which it is intended.

Especially desirable features of my invention are the means whereby the indicating apparatus may be adjusted to compensate for the number of "lines up" and the single scale and double ended pointer, which when properly manipulated, gives an accurate direct reading in tons of weight on the hook and also a direct reading in tons, of the weight of the drill string and tools on the bottom of the well hole.

It will be understood that minor changes in the size, form and construction of the various parts of my improved weight indicator for deep well drilling rigs may be made and substituted for those herein shown and described without departing from the spirit of my invention, the scope of which is set forth in the appended claims.

I claim as my invention:

1. In a weight indicator for well drilling rigs having a drilling cable and a calf wheel, an anchored base, a lever fulcrumed at one end on said base and provided with a plurality of connected apertures located at different distances from its fulcrum, said apertures being distinctive marked, a rigid member, means for detachably securing the lower end of said rigid member to any one of the apertures in said lever, means connecting said rigid member to the cable of the drilling apparatus adjacent the calf wheel, a second lever fulcrumed intermediate its ends and having one end connected to said first mentioned lever, a fluid cushion engaged by the free end of said second mentioned lever, an adjustable duplex pressure gauge and a connection from said fluid cushion to said pressure gauge.

2. In a weight indicator for a well drilling apparatus, having a cable and a calf wheel, a lever fulcrumed at one end, said lever being provided in its intermediate portion with a slot extending longitudinally thereof, there being spaced distinctive markings on said lever adjacent said slot, a rigid member having one end connected to the cable adjacent the calf wheel, the other end of said rigid member being adjustably arranged in said slot, said lever being provided between its free end and said slot with an aperture for the reception of a cable, a second lever fulcrumed intermediate its ends, one end of which second mentioned lever is connected to the free end of the first mentioned lever, a fluid cushion actuated by the free end of said second mentioned lever and a pressure gauge connected to said fluid cushion and adapted to be actuated by pulling strains impressed on said cable and transmitted by said rigid member to the first mentioned lever.

3. In a weight indicator for a well drilling apparatus having a cable and a calf wheel, a base, a lever fulcrumed at one end on said base, said lever being provided intermediate its ends with a longitudinally extending opening formed by a series of connected apertures, said lever bearing distinctive markings adjacent said apertures, a rigid member having one end adjustably arranged in said opening, the other end of said rigid member being connected to the drilling cable above the calf wheel, a second lever fulcrumed intermediate its ends on said base, one end of which last mentioned lever is connected to the free end of the first mentioned lever, a fluid cushion actuated by the free end of said second mentioned lever and an adjustable pressure gauge connected to said fluid cushion and adapted to be actuated by pulling strains impressed on said cable and transmitted to said first mentioned lever.
